UNITED STATES PATENT OFFICE.

WILLIAM C. GRUNOW, OF CHICAGO, ILLINOIS, ASSIGNOR OF ONE-HALF TO BERTRAM J. GRIGSBY, OF CHICAGO, ILLINOIS.

SOUND REPRODUCER.

Application filed March 10, 1925. Serial No. 14,527.

My invention relates to telephones, particularly to loud speaking telephones, such as are frequently used in connection with wireless receiving apparatus.

In my experiments I have found that the elasticity or free vibrating movement of the diaphragm is sensibly affected by a pumping action which the diaphragm, when vibrating, must perform in alternately compressing and sucking the air in the casing of the unit. This casing, for all practical purposes, is usually made air tight, and the conductors are led through a fairly tight outlet opening. A diaphragm, particularly in a loud speaking unit, should have perfect elasticity, that is, it should be able to respond efficiently through the entire range of variations in the voice currents without blasting or failing to reproduce clearly. The chief difficulty with the diaphragm, as heretofore constructed, is its inability to respond to weak currents as well as to strong currents, due to its lack of a free or natural vibrating movement. Unnecessary pressure on the under side of the diaphragm due to condensation and rarefaction of the air in the casing as the diaphragm vibrates has hindered to a certain extent this free or natural vibrating movement.

An object of my invention is the provision of means for removing this impediment to the free action of the diaphragm, particularly by furnishing air holes or vents in the casing to relieve any appreciable pressure or suction effect on the diaphragm.

A further object of my invention resides in the adjustability of said air holes so as to vary, if desired, the pressure on the diaphragm. This variation may be made at any time to secure improved results, if it is found that the action of the diaphragm will be assisted by a change in the pressure, either by relieving it entirely, or by allowing it to be varied.

My experiments have proved the value of this improvement. By closing the air holes while the unit is reproducing and by thereafter suddenly removing the closure from the openings, it will be easily noted that the volume of sound reproduced is perceptibly increased.

In order to apprise those skilled in the art how to construct and practice my invention, I shall now describe an embodiment thereof

in connection with the accompanying drawings forming a part hereof.

In the drawings:

Figure 1 is a vertical sectional view through a sound reproducing unit embodying my invention;

Fig. 2 is a view of this unit with the cover removed, looking downwardly on the permanent magnet, the coils and the openings in the base of the casing, this view being drawn on a smaller scale than Fig. 1;

Fig. 3 is a view similar to Fig. 1, but illustrating merely the lower portion of the same to show the means I employ for opening and closing these openings in the base of the unit; and

Fig. 4 is a bottom plan view of the device shown in Fig. 3, but drawn on a smaller scale.

The sound reproducer 1 comprises a cap 2 and cup 3, in which a permanent magnet 4 and its coils 5 are carried, and a diaphragm 6 adapted to be seated in the cap 2.

Permanent magnet 4 is in the form of a horseshoe and is adapted to have its ends secured to the base 7 of cup 3 by means of bolts 8. Pole pieces 10 extend inwardly from the ends of permanent magnet 4, having their ends turned upwardly to receive the coils 5. Coils 5 may be of any standard construction, comprising the ordinary spools about which winding 11 may be suitably wound. The winding of each spool is preferably attached to terminals 12, secured by bolts 13 upon a strip of insulation 14. Terminals 12 are formed with opposed terminal lugs 15, spaced apart a predetermined distance to permit the current to jump the air gap in the event of an overload in the telephone circuit, thereby preventing the overload from burning out the windings 11. As seen in Fig. 4, the bolts 13 extend through the base 7 of cup 3 for the purpose of permitting the conductors of the telephone circuit to be connected to the unit.

Openings 18 may be furnished in base 7 of the cup 3. These openings may be of any suitable size and disposed in any desired manner. They are, however, of a size sufficient to relieve the pressure of condensation and rarefaction of the air within the chamber on the diaphragm when the latter vibrates. It will be noted that openings 18 are so disposed as to relieve the pressure

equally on opposite sides of this chamber and by referring to Fig. 3, there will be seen a pair of shutters 19 furnished for the purpose of opening and closing these openings

5 18. Shutters 19 have an extension arm 20 pivotally mounted at 21 and connected to the intermediate links 22. The opposite ends of these intermediate links are pivotally connected to an operating link 23.

10 Link 23 may be provided with a slot 24, in which a fixed pin 25 is guided, the purpose of which is to maintain the link in a suitable manner on the under side of the sound reproducing unit. A right angular 15 projection 26 may be formed on link 23 and this right angular projection may extend to any distance, so as to be accessible for manipulation during the operation of the unit. Link 23 may be moved back and forth to 20 swing the shutters 19 in either closed or open positions. The closed position is shown in full lines in Fig. 4, while the open position is shown in dotted lines.

Assume that the sound reproducing unit 25 is in operation and it is desired to increase its volume. All that it is necessary for the operator to do is to grip the projection 26 and move it outwardly so as to swing the shutters 19 away from the openings 18. 30 The mechanical connection to the shutters may be arranged to move the shutters only partially from over the openings 18, so as to vary the sound by relieving only a part of the pressure in the chamber.

35 I have found that the above construction has given good results and not only has increased the volume, but has produced better tone quality.

Many other forms in which this invention 40 may be embodied will occur to those skilled

in the art and the fact that I have specifically illustrated and described but one of them is not intended as a limitation.

I claim:

1. Sound reproducing means comprising in combination a casing, a diaphragm, electrical means for vibrating said diaphragm, and means for varying the air pressure against said diaphragm, said means including openings in said casing and pivotally mounted shutter members serving as adjustable closures for said openings, links extending from the ends of said shutter members, and a operating element pivotally connected to said links for common control of said shutters at a remote point from said openings.

2. Means for controlling a plurality of shutters for openings provided in a casing of an electrically operated telephone unit to vary the pressure against one side of the diaphragm thereof comprising toggle mechanism operatively connected to said shutters and a common operating element operatively connected to said links to provide a remote control for said shutters.

3. Means for preventing the action of the air within the diaphragm chamber from hindering the free vibratory movement of diaphragm of an electrically operated telephone unit comprising a plurality of shutters serving as closures for openings communicating with said chamber, and a remotely operated lever operatively connected to said shutters and extending outwardly a distance to provide a common control for said shutters.

In witness whereof I have hereunto subscribed my name.

WILLIAM C. GRUNOW.
